S. H. PARVIN.
PARALLEL ATTACHMENT FOR T-SQUARES.
APPLICATION FILED FEB. 13, 1920. RENEWED JAN. 12, 1921.

1,369,263.

Patented Feb. 22, 1921.

UNITED STATES PATENT OFFICE.

STANLEY H. PARVIN, OF DAYTON, KENTUCKY.

PARALLEL ATTACHMENT FOR T-SQUARES.

1,369,263.

Specification of Letters Patent. Patented Feb. 22, 1921.

Application filed February 13, 1920, Serial No. 358,380. Renewed January 12, 1921. Serial No. 436,859.

To all whom it may concern:

Be it known that I, STANLEY H. PARVIN, a citizen of the United States, residing in Dayton, in the county of Campbell and 5 State of Kentucky, have invented certain new and useful Improvements in Parallel Attachments for T-Squares, of which the following is a specification.

The objects of my invention are to provide 10 means for automatically holding the T-square in proper position upon the drawing board under tension; to provide means for easily and quickly regulating said tension; to so construct and arrange the parts 15 of the attachment as to be easily and quickly applied to hold T-squares of varying sizes upon drawing boards of varying sizes; to so construct and arrange said parts as to always be entirely out of the way of the 20 draftsman, and to provide means for automatically taking up any slack in the T-square holding wire due to variation caused by sliding the T-square along the end of the drawing board.

25 My invention consists in the parts and in the combination and arrangement of parts as herein set forth and claimed.

In the drawings, which serve to illustrate my invention:

30 Figure 1 is a plan view of a drawing board with T-square and triangle placed thereon ready for use in drawing and showing my attachment by which the T-square is held in proper relation to the drawing board, and

35 Fig. 2 is an end view of the drawing board and T-square held thereon by means of my attachment.

In the embodiment of my invention as illustrated, 1 represents a drawing board; 2 40 is a screw eye secured in the end of the drawing board and to which one end of a T-square holding wire is attached.

The T-square 4 is provided with a sheave 6 attached to the under side of the head of 45 the T-square by screw 5. Holding wire 3 tracks over said sheave and over sheave 7 mounted in screw support 8 fastened to one of the upper corners of the drawing board, said holding wire tracking over said sheave 50 and being attached to tension spring 9 connected to screw stem 10 which is adjustably connected to adjusting nut 11 mounted in screw bracket 12.

55 It will thus be seen that my invention is of very simple and economical construction,

comprising few parts which are easily attached to or detached from a drawing board simply by the attaching or detaching of four screw members, as the case may be. It will also be seen that the T-square 4 may be 60 drawn to the lower edge of the board and that there are no projecting parts of the attachment which interfere with the convenience of the draftsman in his work, or which prevent the board from resting upon a table 65 in a tilted position. It will further be seen that a given attachment can be used upon a small drawing board or one of large dimensions, it being understood that when it is applied to a larger board the member 12 70 will be moved nearer to member 8, allowing more of the holding wire 3 to extend across the end of the board instead of along the upper edge thereof. Likewise, when it is desired to substitute one size of T-square for 75 another upon the board, it becomes necessary to adjust the tension from the one to the other and this can be readily accomplished by simply turning the nut 11 to provide for either a larger or smaller T-square 80 as the case may be.

While I have shown and illustrated my attachment for use upon the ordinary drawing board, it may also be attached to the ordinary table or desk and used to great advantage thereon.

While I have illustrated a particular construction and arrangement of parts, it will be understood that I do not desire to be limited to the precise details of construction 90 herein set forth.

What I claim is new and desire to secure by Letters Patent is:

1. In combination with a drawing board, a T-square, a sheave mounted thereon, a 95 sheave mounted on said drawing board, a holding-wire attached to said drawing board and tracking said sheaves, a tension member connected to said holding wire, adjusting means connected to said tension means and 100 means for attaching said adjusting means to said board.

2. In combination with a drawing board, a T-square, a sheave mounted thereon, a 105 sheave mounted on said drawing board, a holding-wire attached to said drawing board and tracking on said sheaves, a tension spring attached to said holding-wire, a screw-stem attached to said tension wire, a screw support attached to said drawing 110

board, and an adjusting nut mounted therein, and adapted to engage said screw-stem whereby suitable adjustment may be made.

3. In combination with a drawing board, 5 a screw-eye attached to near one corner of said board, a sheave support mounted near the other corner thereof, and a screw bracket mounted on one edge of said board, a T-square, a sheave mounted on the head 10 thereof, a holding-wire attached to said screw-eye and tracking over said sheaves, a tension spring attached to said holding-wire, a screw-stem attached to said tension spring and an adjusting nut positioned in said

screw bracket and threaded upon said screw- 15 stem for the purposes set forth.

4. In combination with a drawing board, a screw-eye attached to one end thereof, a T-square, a sheave mounted on the lower side of the head of said T-square, a sheave mounted 20 upon the upper edge at the corner of the drawing board, a bracket attached to the upper edge of said drawing board, a holding-wire attached to said screw-eye and tracking said sheaves and means for adjustably and automatically regulating the 25 tension of said holding-wire.

STANLEY H. PARVIN.
